UNITED STATES PATENT OFFICE.

THEODORE H. SCHREIBER, OF BALTIMORE, MARYLAND.

RAILWAY BLOCK SYSTEM.

1,126,576.

Specification of Letters Patent.

Patented Jan. 26, 1915.

Application filed August 20, 1909. Serial No. 513,844.

To all whom it may concern:

Be it known that I, THEODORE H. SCHREIBER, a citizen of the United States, residing at Baltimore city, in the State of Maryland, have invented certain new and useful Improvements in Railway Block Systems; and I do hereby declare the following to be a full, clear, and exact description of the invention, such as will enable others skilled 10 in the art to which it appertains to make and use the same.

This invention relates to railway block systems and has special reference to a railway block system for controlling the movements of trains by electricity. It is necessary in systems of this character that provision should be made whereby the breakdown of the signaling or train controlling system will stop the train or display the 15 danger signal. In order to do this the signal must be set to "Clear" and the train released from the automatic control common in such systems by the passage of a current through the electric circuit and not 20 by the breaking thereof.

The principal object of the present invention is to provide an improved system of this character whereby the trains running over a track will be prevented from 25 passing from one block to another except upon the passage of an electric impulse through the train controlling circuit. It is also necessary in systems of this character that the train operator should have definite 30 information as to the condition of the block system and that this information should be given him in each and every block of the system.

A second object of this invention is to 40 provide means whereby the train operator may have accurate information as to the condition of the system so that he may know whether any difference exists in either the mechanical or electrical parts of the apparatus connected therewith. It is furthermore advisable that the train operator should be informed of the condition of the track for 45 several blocks in advance of the train so that he may use precautionary measures to prevent too close an approach of one train to another or to prevent a train running into a block under the control of the automatic stop at too great a speed.

The third object of this invention is to 50 provide means for informing the train operator of the condition of the track and the

presence of another train several blocks in advance of the train whereon he is stationed and that this means shall indicate caution in the event of any breakdown of the system as well as any damage to the track or the presence of a second train. In systems of this character it is absolutely essential 60 that the system shall work correctly whether a train be running in one direction or another on the track, as for instance, whether a train is running forward or backing up on a double track railroad or whether a train is running in one direction or the other on a single track railroad.

The fourth object of this invention is to 70 provide an improved means of this character which will operate without reference to the direction in which the train is running.

With the above and other objects in view, 75 as will be hereinafter apparent, the invention consists in general of a block system of improved character wherein a train is permitted to move from one block to another only upon the passage of an electric 80 current through a train controlling mechanism, in combination with certain signaling and indicating mechanism for the purpose of notifying the train operator of the condition of the track and the system.

The invention further consists in certain 85 novel details of construction and combinations of parts hereinafter fully described, illustrated in the accompanying drawings, and specifically set forth in the claims.

In the accompanying drawings, like characters of reference indicate like parts in the several views, and Figure 1 is a dia- 90 grammatic view of the wiring applied to the track in a system constructed in accord- 95 ance with this invention. Fig. 2 is a rear elevation of a locomotive cab showing the rolling stock supported mechanism used with this system located therein. Fig. 3 is a side elevation of the rear end of the 100 locomotive equipped with the rolling stock supported mechanism shown in Fig. 2, the cab having a portion of the side broken away the better to disclose the interior. Fig. 4 is a view similar to Fig. 2 showing a 105 modified form of the mechanism. Fig. 5 is a view similar to Fig. 3 showing the modification illustrated in Fig. 4. Fig. 6 is an enlarged detail side view of a portion of the mechanism illustrated in Figs. 2 and 3. 110 Fig. 7 is an end elevation of the mechanism shown in Fig. 6. Fig. 8 is a detail end ele-

2
5 vation of the train operator's signaling device, the casing which surrounds the mechanism being removed the better to disclose the same. Fig. 9 is a side view of the mechanism shown in Fig. 8. Fig. 10 is a detail view of a means for controlling an engineer's brake valve. Fig. 11 is a detail view of a contact shoe adapted to be used with this invention. Fig. 12 is a view showing 10 the method of attaching the foot of the rack bar to the journal box hereinafter referred to. Fig. 13 is a detail view showing the method of attaching the contact wheel hereinafter referred to. Fig. 14 is an enlarged 15 view partly in section through a modification of the means for locking certain plates together. Fig. 15 is a partial plan view of the bottom plate shown in Fig. 14. Fig. 16 is a sectional view on the line 16—16 of 20 Fig. 15. Fig. 17 is a detail view of the foot of the locking bar.

In the present embodiment of this invention the same has been shown as applied to a locomotive engine but it will be obvious that 25 this invention may be equally as well applied to any form of rolling stock common to railroads, as for instance, the invention might be used with an electric car or locomotive, or the rolling stock supported mechanism might be carried in a passenger car. It will also be obvious that in order to utilize 30 this invention for different constructions of air brakes and for placing the same in different positions minor changes will have 35 to be made in the form, proportions and details. These changes will not, however, affect the principles of the invention and it is not therefore desired that the present specification and drawings be regarded as 40 setting forth the only form in which this invention can be embodied, but the present description and drawings are merely to be regarded as typical of all forms that come within the scope of the appended claims.

45 In whatever way the invention may be embodied it is necessary that the track on which the rolling stock runs should be divided into blocks which are insulated from each other.

50 In the drawings the track is indicated by the numeral 20 and the different blocks are separated from each other by insulation 21. In order to facilitate the understanding of the various circuits the right hand end of 55 Fig. 1 will be referred to as east and the left hand end of that figure as west. Connected to the rails of each block are wires 22. One of these wires leads through suitable resistance 23 to one pole of a battery 24 while the other wire leads to the other pole of said battery.

60 In the diagrammatic view disclosed in Fig. 1 the different blocks are indicated by consecutive letters of the alphabet as A, B, C, 65 D, E and F but six blocks are shown as this

number is sufficient to disclose the working of the circuits. It is obvious, however, that the track may be divided into as many blocks as are deemed necessary. Adjacent each of the blocks is a battery well 25 wherein is located a battery 26. In Fig. 1 a portion of the circuits have been diagrammatically shown on one side of the track and a second portion on the other side of the track. It is to be understood that the mechanism controlling the circuit for each block is all located together and the dotted lines 27 opposite each of the blocks indicate a casing which contains this mechanism. In each of the casings 27 are supported magnets 28, 29, 30, 31, 32 and 33. Pivoted adjacent the pole of each of these magnets are bars 34, 35, 36, 37, 38 and 39. Each of these bars is provided with an armature 40 and has suitable insulation 41 interposed between its ends. Upon the end of each of the bars is carried a contact, there being one contact for each bar and these contacts are indicated respectively at 42, 43, 44, 45, 46 and 47. Connected to one rail of each of the blocks is a wire 48 which leads to one pole of the respective battery 26 belonging to that block. From each battery 26 leads a wire 49 which runs to a contact 50 so located as to be struck by the contact 42 when current passes through the magnet 28 of that block and the armature 40 is attracted. Adjacent one or both of the rails of the various blocks are certain contact elements arranged to be struck by a rolling stock supported contact making element and these elements are for the present to be considered solely in their electrical functions. Considering these contacts in this manner each block is provided with four contacts arranged in succession as indicated at 51, 52, 53 and 54. These contacts are insulated from each other by suitable insulating blocks 55. From each of the contacts 51 extends a wire 56 which runs to a contact 57 in the casing 27 of the respective block and this contact is arranged to be struck by the contact 43 when current passes through the respective magnet 29. Adjacent the contact 50 in each casing and arranged to be struck by the contact 42 at the same time is a contact 58 from which a wire 59 leads to a contact 60 adjacent the contact 57. Now, considering this portion of the circuit. When the rail 20 is brought into electrical 120 communication with the contact 51 by the passing of a locomotive current will flow from the battery 26 through the wire 49, contact 50, contact 42, contact 58, wire 59, contact 60, contact 43, contact 57, wire 56, 125 contact 51, through the rolling stock to the rail 20, wire 48 back to the battery 26.

130 It will be obvious that any interruption of the circuit through either the magnet 28 or magnet 29 will permit either the contact 42

or the contact 43 to fall away from the respective contact points 50 and 58 or 57 and 60 and that the circuit just described will thereby be interrupted. From the contact 52 a wire 61 runs to a contact point 62 which is adapted to be struck by the contact 47 when the magnet 33 is energized by the passage of a current therethrough. Adjacent the contact point 62 and also arranged to be struck by the contact 47 is a contact point 63 from whence a wire 64 leads back to the battery 26. Now, when the train contact device strikes the contact 52 current will flow from the battery 26 through the wire 64, contact point 66 and also engageable with the contact 61, contact 52, through the rolling stock to the rail 20, and back through the wire 48 to the battery 26. From the contact 53 a wire 65 leads to a contact point 66 which is adapted to be struck by the contact 44 when the magnet 30 is energized by the passage of a current therethrough. Adjacent the contact point 66 and also engageable with the contact 44 is a contact point 67 from which a wire 68 leads to the wire 49 thus forming connection with the battery 26. Now, so long as current is passing through the magnet 30 when the train supported contact strikes the contact 53 current will flow from the battery 26 through the wire 49, wire 68, contact point 67, contact 44, contact point 66, wire 65, contact 53, through the rolling stock back to the rail 20 and from this through the wire 48 back to the battery 26. From the contact 54 a wire 69 leads to a contact point 70 adjacent which is a contact point 71 and both of these contact points are adapted to be struck by the contact 45 when the magnet 31 is energized by the passage of a current therethrough. From the contact 71 a wire 72 leads to a contact 73 which is adapted to be struck by the contact 46 when the magnet 32 is energized by the passage of a current therethrough. Adjacent the contact point 73 is a contact point 74 from whence a wire 75 connects with the wire 64 which leads back to the battery 26. Now, so long as both the magnet 31 and the magnet 32 are energized when the contact 54 is engaged by the rolling stock supported contact current will flow from the battery 26 through the wire 64, wire 75, contact point 74, contact 46, contact point 73, wire 72, contact point 71, contact 45, contact point 70, wire 69, contact 54, through the rolling stock back to the rail 20 and from thence through the wire 48 to the battery 26. If the current through either the magnet 31 or the magnet 32 be interrupted this circuit will be broken by the dropping away of either the contact 45 or the contact 46 from the respective contact points wherewith these contacts engage. It will now be obvious that the arrangement of the contacts 51 and 53, when the train is considered as passing from the west to the

east, will be identical in electric circuits with the arrangement including the contacts 54 and 52 in the order named when the train is passing from the east to the west.

Considering now the circuits which lead to the various magnets. In order to understand the exact manner in which these circuits run one of the blocks will be taken and the circuits described which run therefrom. Assume, in the first instance, that this is the block D. From the rail 20 of the block D runs a wire 76 which extends to the magnet 28 of the block C. From the magnet 28 of the block C runs a wire 77 which extends to the magnet 29 of the block B. From the magnet 29 of the block B runs a wire 78 which extends to the magnet 30 of the block A. From the magnet 30 of the block A runs a wire 79 which extends to the magnet 33 of the block one block to the right of block F. From the magnet 31 of the block E a wire 80 extends to the magnet 32 of block F. From the magnet 32 of the block F a wire 81 leads to the magnet 33 of the next block east, this block not being shown in the diagram but being provided with the same magnet arrangement as the other blocks, as hereinbefore noted. From the magnet 31 of the block D a wire 82 leads back to the other rail 20 of the block D. It will thus be observed that each of the blocks in this system is wired to the magnets of three blocks west and three blocks east of that block. Now, under ordinary circumstances, so long as the rails 20 are not broken or a train is not in the block or the wiring system is intact and without short circuits or other faults, current will flow from one of the rails 20 of each block through the wire 76 leading from that block, the magnet 28 of the next block west, the wire 77 leading therefrom, the magnet 29 of the second block west, the wire 78 leading therefrom, the magnet 30 of the third block west, the wire 79, the magnet 33 of the third block east, the wire 81, the magnet 32 of the second block east, the wire 80, the magnet 31 of the first block east, the wire 82, the other rail 20, the wire 22, the resistance 23, the battery 24, and the wire 22 back to the first rail. So long as this current continues to flow the various magnets in the circuit will continue to attract their armatures and consequently keep the circuits leading to the contacts 51, 52, 53 and 54 constantly closed. If, however, either of the rails 20 breaks, or in any way the circuit just described become deranged by interruption, short circuits or any other cause whatever, the circuit through these magnets will be broken and the armatures allowed to fall away therefrom so that current will no longer flow through the circuits connected to the contacts 51, 52, 53 and 54. Furthermore, in the event that rolling stock of any

kind enters a block the battery 24 in that block will be at once short circuited and this will, of course, produce precisely the same result as fracture of the rails or short circuiting of the wires connected thereto with the consequent interruption of the circuits connected to the track contacts 51 to 54 above mentioned. Now, if suitable mechanism be provided on the rolling stock this interruption of the circuit may be caused to 10 actuate a valve and display a signal. To this end a mechanism is provided which will now be described, it being understood, as previously noted, that this mechanism may be changed in detail to suit different purposes for which it may be intended and different locations about the rolling stock where it may be fitted.

In the form of the invention disclosed in 20 Figs. 2 and 3 and the details referring to these figures the contacts 51 to 54 are arranged adjacent one of the rails 20 and these contacts comprise relatively short sections of rail which have between them the insulation 25 55. These sections are so arranged that they slope upward in the middle so that the upper surface is anticlinal in the direction of the length of the track.

At 83 is indicated a portion of a locomotive which is provided with frames 84. On 30 one of these frames are mounted guides 85 wherethrough passes a bar 86 arranged to slide vertically through the guides. At the bottom of this bar the same is reduced as 35 shown at 87 and this reduced end is provided with a suitable perforation to receive a pin 88. On the pin 88 is swung a foot block 89 provided with spaced ears 90 for the reception of the reduced end 87 so that while the 40 block is permitted to swing longitudinally of the locomotive all side movement is prevented.

At 91 is a shoe which is provided with 45 flanges 92 and this shoe and flanges have upwardly curved ends as clearly shown in Fig. 11. This shoe is secured to the foot 89 by means of bolts 93 which pass through insulating sleeves 94 and the shoe is further insulated from the foot 89 by an insulating 50 plate 95. The bar 86 is formed on one face with rack teeth 96. Supported in suitable bearings 97 is a shaft 98 whereon is keyed or otherwise securely fastened a gear 99 which meshes with the rack formed on the bar 86. Upon the shaft 98 is a bevel gear 100 and this bevel gear meshes with a second bevel gear 101 which is carried on a shaft 102, the gear 101 being splined on the shaft 102 so that the gear is freely movable 55 along that shaft. It is to be noted that the bearings 79 are secured to a frame 103 which is mounted on the axles 104 of the rear wheels of the engine, the axles revolving freely in the frame mounting. The object 60 of this is that the shaft 98 may at all times

remain at an even height above the rails. The shaft 102 is mounted in a bearing frame 104 which is secured in any convenient place to the floor of the cab and on this shaft is a second bevel gear 105 which meshes with a 70 bevel gear 106 carried on a shaft 107 supported in bearings 108 suitably mounted in the cab of the engine. The shaft 102 extends upward above the gear 105 and upon the upper end of this shaft is a plate 109 75 which is provided with a slot 110.

At 111 is shown a valve, here indicated as an engineer's valve in an air brake system. It will be obvious, however, that this valve may be a steam valve or any other form of 80 rotary valve than that shown, the disclosure being merely typical of the common form of valve. This valve is provided with a stem 112 whereon is mounted a plate 113 having a perforation 114 formed therein and this perforation is arranged to register with the slot 110. The plate 113 is further provided with a handle 115. Mounted above the plates 109 and 113 is a magnet 116 and below this magnet is its armature 117. Attached to the 90 armature 117 is a pin 118 and this pin is supported in a suitable guide 119 formed on the disk 118. By means of this construction it will be seen that so long as no current 95 passes through the magnet 116 the armature 117 will not be attracted by this magnet. This will permit the pin 118 to remain with its lower end in the opening 114 and slot 110. It will thus be seen that when the pin 118 engages the end of the slot 110, the plates 100 113 and 109 are locked against further unrelated rotation. This magnet 116 is connected to the shoe 91 by means of a wire 120 and to the rail 20 by means of a wire 121 which leads to some part of the engine which 105 is in electrical connection with the rail. Now, considering this portion of the device in connection with the circuits previously 110 described. As the locomotive passes along the track the shoe 91 will contact with the 111 track contact 51. This will raise the shoe and the rack 96 will rotate the gear 99 and through the bevel gears 100 and 101 will rotate the shaft 102. Now, so long as the pin 118 remains down the rotation of the shaft 115 102 will cause the plate 113 to rotate as the two plates 109 and 113 will be locked together by the pin 118. If, however, at the time that this shoe contacts with the track contact 51 a current is flowing through the 116 circuit embracing the contact 51 the magnet 116 will be energized and the armature 117 be attracted thereto. The plates 109 and 113 will thus be unlocked from each other as the pin 118 will be drawn out of the slot 110. The plate 109 will thus be free to rotate 120 without rotating the plate 113. It will now be plain that any interruption of the circuit 125 passing through the contact 51 will operate to set the brakes on the train. This is true 130

135

for a train running from west to east but where the train runs from east to west the contact 54 is the one which operates in the manner described. Considering this feature 5 of the invention in connection with the blocks shown in Fig. 1. Suppose the train to enter any of the blocks there shown and that a second train is either in the block just ahead or in the second block ahead. If the 10 train first mentioned enters the block D and a train is in the block E the magnet 28 for the block D will be deenergized by the presence of the train in E. This will break the connection between the contacts 50 and 58 15 and the contact 42. Thus no current will flow through the magnet 116 and the brakes will be set as the valve will be turned. In like manner if the second train is in the block F the magnet 29 of the block D will be 20 deenergized and the circuit will be broken between the contacts 57 and 60 and contact 43. It will be noted that the operation is effected without reference to the direction of movement of the second train as the mere 25 presence of that train in either the first or second block ahead will interrupt the current through the magnet 116. Furthermore, in the event of the rails breaking or any other interruption of the current in either 30 of the two blocks ahead or in the circuit itself the brakes will still be applied. It will thus be observed that the flow of the current through the magnet 116 is essential 35 to permit the train to pass from one block to another.

For the purpose of insuring the application of the brakes in case of any derangement of the parts below the plate 109 this plate has connected thereto a spring 122 40 which normally tends to rotate the plate in the direction of the arrow on the shaft 102. This spring while strong enough to operate the valve 111 is not sufficiently strong to put the remainder of the parts in motion. It is 45 possible that some of the mechanical structure might fail to operate and it is essential that the engineer should be informed that all parts of the device are in proper order so that provision is made for a signal. Within 50 in the cab of the locomotive is a casing 123 wherein are certain operating parts for a signal which will now be described. Upon the shaft 107 is a gear 124 which meshes with a rack 125. This rack is formed on 55 the lower end of a bar 126, the upper end of which projects into the casing 123. Mounted adjacent the upper end of this bar is a post 127 whereon is fixedly mounted a collar 128. At one end of this post is rotatably mounted an arm 129 whereto is fixed a semaphore blade 130. A coil spring is disposed around the post 127 and has its ends bearing against the collar 128 and the arm 129. A second arm 131 extends from this 60 end and is provided with the usual spectacle 65

frame 132 fitted with the ordinary glasses. In the present instance the glasses are red and white respectively. Above the post 127 is a post 133 on which is mounted a semaphore of precisely similar construction and to which the same reference characters apply. This upper semaphore is provided with blue and white glasses in the present instance. At the inner end of the lower sleeve 128 is a disk 134 provided with a marginal notch 135 and a second marginal notch 136. On the bar 126 is formed a guide boss 137 wherethrough passes a bar 138 provided with a collar 139 and having a forked end 140. A spring 141 is held between the collar 139 and the boss 137 and normally presses the collar away from the bar 126. Between the arms of the fork 140 is mounted a block 142 which slides in a slot 143 formed in a bar 144 pivoted as at 145 to the casing. This bar 144 is provided with a magnet armature 146 and a magnet 147 is secured in the casing in such position as to attract the armature 146 when a current passes therethrough. This magnet 147 is connected in 70 series with the magnet 116, the wire 121 leading through the magnet 147 before its return to the track connection. What may be termed the inner end of the bar 138 is provided with a lip 148 and this lip is so 75 arranged as to engage the notch 135 when the magnet 147 is energized and the bar 144 moved inward toward the magnet. When the magnet 147 is not energized the spring 141 will force the lip 148 toward the bar 126 80 and the lip will not engage the notch 135 if the bar 126 be moved upward. Now, when the shaft 107 is rotated by the shoe rising up on the incline of the track contact, if a current be sent through this contact the 85 magnet 147 will be energized. This will cause the hook 148 to move to position to engage the notch 135. The result of this will be that as the upward movement of the bar 126 continues the lower semaphore arm 110 90 130 will be depressed. Pivoted on a boss 149 is a bent lever 150 the end of which is arranged to enter the notch 136. The end of this lever is normally urged toward the center of rotation of the disk 134 by means 95 of a spring 151 one end whereof is attached to the lever 150 and the other to a suitable post 152 mounted on the casing 123. Now as the bar moves up and the disk rotates the notch 136 is brought to register with 100 the end of the lever 150 and this lever enters the notch thus holding the semaphore arm 130 depressed. As the shoe passes over the track contacts and the bar 126 again descends the lower semaphore arm 130 remains 105 down, this being the position of "safety" or "proceed" as is usual in railway signals. In order to release the semaphore arm certain provision is made. This consists of a small 110 spring arm 153 which is fixed to the bar 126 115 120 125 130 135 140 145 150 155 160 165 170 175 180

and is arranged to contact with the end of the lever 150 adjacent said bar. This arm is arranged to permit the bar to fall freely past the end of the lever 150 but at the beginning of the upward movement of the bar 126 the arm 153 strikes against the end of the lever 150 and pulls the other end out of the notch 136. The weight of the spectacle end of the semaphore arm immediately causes the arm to rise and take the position of "danger" or "stop." Now, if at the same time the magnet 147 is energized the semaphore will be immediately returned to the position of "safety" or "proceed." If, however, the magnet 147 is not energized the semaphore arm 130 will remain up, this giving the engineer a clear indication that no current has been through the contact 51 or the contact 54 according to which way the engine is running. It will be noted that this effect will take place whether the engine is running ahead or backing up and without reference to the direction of its movement. Now, as has been previously described, the presence of a train in either of the two blocks immediately ahead of the train whereon this mechanism is located will prevent the passage of an electric current through the magnet 116 and consequently through the magnet 147. The upper semaphore is likewise provided with a disk 154 which has a notch 155 similar to the notch 135 but opening upward instead of downward as does the notch 135. The bar 126 is provided with a further guide boss 156 wherethrough passes a bar 157 provided with a collar 158 and having a forked end 159. A spring 160 is mounted on this bar between the collar and the boss for the same purpose as the spring 141. This bar is provided on its inner end with a downwardly turned lip 161 adapted to engage the notch 155. In the forked end of this bar is a block 162 moving in a slot 163 formed in an arm 164 similar to the arm 144 and like it provided with a magnet armature 165. A magnet 166 is positioned to attract this armature and this magnet is also in series with the magnet 116 and consequently in series with the magnet 147. Now, this end 161 is so arranged that at the extreme upper limit of the movement of the bar 126 the end 161 will be slightly above the lip of the notch 155. It will be observed that this extreme upper limit is only reached when the shoe is on either the contact 52 or the contact 53. It will be observed that by reason of the end 161 being downwardly turned and the notch 155 opening upward the engagement of this end with the notch can only take place during the downward movement of the bar 162. Now, this downward movement, assuming the train is running from west to east, takes place on the contact 53. If, when the shoe is on this contact 53, the electric current passes through the contact, the magnet 166 will be energized and the armature 165 attracted thereto. Now, as the bar 162 continues to descend, the hook 161 will engage the notch 155 and the upper semaphore arm 130 will be drawn downward. Now it is to be observed that the disk 154 is substantially twice the diameter of the disk 134 so that once the hook 161 is engaged in the notch 155 the entire downward movement of the bar 126 will turn the upper semaphore arm 130 to the same angular position as the lower semaphore arm is turned by one-half the upward movement. Furthermore, this hook will retain the semaphore in its downward or "clear" position until the next series of track contacts are reached when the arm will be permitted to rise and the hook to disengage the notch if no current passes through the magnet 166. The downward position of this semaphore arm indicates "clear" for the third block ahead while the upper position indicates "caution." If the magnet 166 does not receive a current from the third step of the track contact the lip 161 will move downward without moving the upper semaphore arm. Now, from an inspection of Fig. 1 it will be observed that, considering the block D, when a train is in this block and a second train is in the third block ahead, the magnet 30 of the block D will be deenergized and the circuit passing through the contact 53 will be broken by reason of the contact 44 falling away from the contact points 66 and 67. In like manner if the rails of this third block ahead be broken or the circuit including the magnet 30 of the block D be in any way faulty, the magnet will be deenergized. The engineer will thus have a cautionary signal for the third block ahead and this cautionary signal will operate like the danger signal to indicate at each block the fact whether the circuit is in proper working order provided no train is in the third block ahead. In passing from east to west the magnet 33 of the block D will in like manner break the circuit through the contact 52 and this whether the train is running ahead or backing up. In order to provide for constant engagement of the lips 148 and 161 with their respective notches throughout the entire movement the notches are made undercut so that even if the circuit be broken through the magnets 147 and 166 the semaphores will make a complete movement provided the circuit has once been made through these magnets. In order to check the upward movement of the lower semaphore arm 130 a dash pot 167 of suitable construction is provided and a plunger 168 movable in this dash pot is connected to this lower arm 130 by means of a rod 169. In the form of the invention shown in Figs. 4 and 5 a slightly different arrangement is provided.

ment is made for the purpose of operating the shaft 102. In this form a frame 170 is provided which is supported on two of the axles of the locomotive, the support for but one being here shown as the other support is similar. In this frame are fitted suitable bearings 171 to receive axles 172 and this frame extends rearwardly from these axles. At 173 are pedestals wherein move bearings 174 which carry a shaft 175 whereon are mounted wheels 176 each of which is provided on its inner side with a supplementary wheel 177 and between the wheels 176 and 177 is suitable insulation 178. The wheels 177 are bolted to the wheels 176 by means of bolts 179 which pass through insulating sleeves 180. The wheels 176 are thus electrically insulated from all other parts of the engine, the object of this insulation being to prevent the transmitting of the current from the wheel 177 to the wheel 176 and consequently to the traction rail at the moment of the contact of both of said wheels with the contact and traction rails. In place of the single set of single track contacts 51 to 54 this form of the invention employs a set of these contacts adjacent each of the track rails as can be clearly seen by reference to Fig. 4. Connected to the boxes 174 are rack bars 181 and these rack bars are insulated from the boxes by means of suitable insulation 182 beneath the feet of the bars, the bars being secured to the boxes by bolts 183 which pass through insulating sleeves 184. The pedestals are in like manner insulated from the frame 170 by means of suitable insulation 185 between the top of the pedestals and the frame. These pedestals are held to the frame by suitable bolts 186 which pass through insulating sleeves 187. At 188 is a shaft whereon are gears 189 which mesh with the racks 181. This shaft is further provided with a third gear 190 which meshes with a rack bar 191 which corresponds in all respects to the rack bar 125 and which actuates the same mechanism as does that rack bar in the previously described form. In this form of the device the wire 120 is connected to one of the bearings 174. In the operation of this form of the invention the wheels 176 normally rest upon the rails 20. When, however, the engine reaches the track contact rails the wheels 177 will engage with these rails and lift the wheels 176 clear of the rails 20. Furthermore, it will be observed that by reason of the wheels 176 and 177 being constantly rotated as the engine moves over the track the latter wheels, when they strike the inclined contact rails, will roll up the incline without jar or shock. As these wheels roll up the incline the rack bars 181 are raised and this rotates the shaft 188 which acts to raise the rack bar 191 and sets in motion the entire train of apparatus previously described.

In the modification illustrated in Figs. 14 to 17 both inclusive there is shown a different form of means for locking a pair of plates such as the plates 113 and 109 together. The plate 113 in this modification is identical with the plate 113 in the previously described form. The plate 109 is, however, replaced by a plate 192. Where the two plates 112 and 113 are connected in the manner previously described the pin 118 must be retracted as soon as the shoe or rolling contact begins to rise. Now, if anything interferes with the making of the contact at this time this movement of the pin will be prevented by reason of its being gripped by the two plates. In order to overcome this difficulty this modification has been devised. It will be noted that the pin 118 is replaced by a pin 193 having oppositely disposed recesses 194 at its lower end and between these recesses is a passage 195. Sliding in the recesses 194 are a pair of wings 196 which are normally held apart by means of a spring 197. The plate 192 is provided at one point with a deep arcuate groove 198 from which extends a shallow arcuate groove 199. Extending around the sides of the arcuate groove 198 are a pair of ribs 200 which terminate short of the beginning of the groove 198 as can clearly be seen from reference to Fig. 15. These ribs 200 are spaced apart to form a slot 201 and from this slot extends a centrally disposed shallow depression or groove 202 which runs substantially the entire length of the shallow groove 199. Between the shallow groove 199 and the deep groove 198 is an abrupt shoulder 203. In the operation of this form of the device it is intended that the plate 192 should have a certain amount of lost motion before the plate 113 is turned thereby. In the present instance the amount of lost motion is equivalent to substantially the length of the deep groove 198. Now, the magnet 116 rests above the pin 193 in the same manner as in the former case and the pin 193 is provided with an armature 204 corresponding to the armature 117.

In order to understand the operation of the device, let it be supposed that the contact strikes the beginning of the contact rail. As soon as this occurs the plate 192 will begin to revolve. This plate will continue to revolve throughout the entire movement of the contact by the contact rail. At any point between the end of the slot 198 and the abrupt shoulder 203 at which a current may be sent through the magnet 116 the armature 204 will be attracted. This will pull the pin 193 upward and compress the wings 196 so that they may slip through the opening 201 between the ribs 200. If no current flows through the magnet 116 the revolution of the plate 192 will bring the 130

shoulder 203 against the lower end of the pin 193 and consequently move the upper plate 112. If the pin is raised by the passage of a current and the current fails the pin will still remain in the raised position by reason of the wings 196 springing out after the bottoms of these wings have been raised above the ribs 200 so that the pin is prevented from dropping back. The plate 192 may then continue to revolve and the lower end of the pin will pass entirely around the shallow slot 199, the extremity of the pin below the wings sliding in the depression 202. When the track contact 15 summit is reached and the shoe or wheel begins to descend the plate 192 will be turned backward and when the opposite limit of its revolution has been reached the lower end of the pin 193 will drop off the ends of the ribs 200 thus resuming the position shown in Fig. 14.

It will be seen that this device permits the current to be applied at any point while the shoe is moving upward so that any failure due to a little dirt on the contact will not stop the engine unnecessarily.

It will be observed that this device may be used for electric railways when desired by omitting the connections with one rail 30 and the insulation between the blocks of that rail.

The operation of the device having been described in detail throughout the specification further description of the action of this form is not deemed necessary.

It is obvious, as previously stated, that minor changes may be made in the form and construction of this invention without departing from the material principles thereof. It is not therefore desired to confine the invention to the exact form herein shown and described, but it is wished to include all such as properly come within the scope of the appended claims.

Having thus described the invention, what is claimed as new, is:

1. In a device of the kind described, a series of track blocks, anticlinally arranged rail sections adjacent each of said train blocks, a rolling stock supported rack bar provided with means insulated therefrom for engaging the anticlinial rail sections as the rolling stock passes along the track, valve controlling mechanism actuated by said rack bar and including a pair of rotatable plates provided with alined perforations, a pin having an armature on one end normally passing through the perforations and connecting the plates, a magnet mounted above said pin, normally open electric circuit connections including said magnet, one end of said circuit connections being grounded to the rolling stock while the other end is connected to the insulated contact means, and an open circuit connected to each of said

blocks and one of the rail sections to complete the circuit through the magnet as the rolling stock passes the rail sections.

2. In a device of the kind described, rolling stock supported valve controlling mechanism, a series of track blocks, anticlinally arranged rail sections adjacent the track of each block, an insulated element arranged to contact with the rail sections as the train passes through the block, mechanical connections between said element and the valve controlling mechanism, semaphore arm supported on the rolling stock, a notched disk connected to said arm to operate the semaphore as the disk is rotated, a bar movable toward and away from said disk, mechanical connections operated by the aforesaid mechanical connection for supporting said bar and moving it tangentially of the disk, a spring normally holding said bar clear of said disk, a guide for one end of said bar, a pivoted lever whereon said guide moves, an armature on said lever, a magnet adjacent said armature, one end of said magnet being grounded and the opposite end being connected through the first named magnet to the insulated element, means adjacent each block to complete a circuit including the track and one of the rail sections whereby current will flow through the magnets when the insulated element contacts with the rail section, and a lip on said bar adapted to engage the notch when the guide is drawn in by the magnet.

3. In a device of the kind described, a series of track blocks, a set of four rail sections adjacent each block and having insulation therebetween, said sections being arranged in anticlinally disposed pairs, separate circuits each including the track and one of said sections, train supported valve controlling mechanism including an actuating element insulated from the balance of the mechanism and arranged to move over said track sections, said mechanism further including a pair of rotatable plates having alined perforations, and a pin provided with an armature upon one end normally held in said perforations to connect the plates, a magnet mounted adjacent said armature to attract the same when a current passes therethrough, a signal actuating mechanism operatively connected to the valve controlling mechanism and a movable simultaneously therewith, said signal actuating mechanism including a longitudinally movable bar, a pair of bars slidable transversely of the first mentioned bar, springs normally urging said bars in one direction, pivotal guide levers for each of said bars, armatures on each of said guide levers, a magnet adjacent each of said armatures, all of said magnets being connected in series and one of the magnets being connected to the insulated element while the last magnet of the series is

- grounded, a pair of semaphore signals pivotally supported on the rolling stock adjacent the paths of said pair of bars, a notched disk connected to one of said semaphores, the notch of the disk opening downward, an upturned lip formed on one of the pair of bars and arranged to engage the notch of said disk as the bars are carried upward, a second disk provided with a notch opening upward, said second disk being connected to the second semaphore and a downwardly turned lip formed on the second of said pair of bars whereby the movement of the bar upward will operate the first semaphore and the movement of the bar downward will operate the second semaphore when current passes through the respective magnets controlling the transversely moving bars. 15
4. In a train control system, a longitudinally movable structure, train stopping apparatus adapted to be operated by a movement of the structure in one direction, signaling apparatus adapted to be operated by the movement of said structure in a reverse direction, and electrically operated means for rendering the longitudinally movable structure operative and inoperative with respect to operating said train stopping and 20 signaling apparatuses. 25
5. In a train control system, a longitudinally movable structure, apparatus adapted to be operated by said structure, a second apparatus adapted to be operated by said structure, electrically operated means adapted when energized to render said structure inoperative with respect to operating the first named apparatus, and electrically operated means adapted when energized to render said structure operative with respect to operating the said second named apparatus. 30
6. In a train control system, a longitudinally movable structure, a ramp with which the same is adapted to engage, apparatuses adapted to be operated by said movable structure, electrically operated means adapted when energized to render said structure inoperative with respect to operating one of said apparatuses, electrically operated means adapted when energized to render said structure operative with respect to operating the other apparatus, and means to electrically connect said electrically operated means in series and with said structure. 35
7. In a train control system, a longitudinally movable structure, train stopping apparatus adapted to be operated by a movement of the structure in one direction, electrically operated means adapted when energized to render said structure inoperative with respect to operating said train stopping apparatus, signaling apparatus adapted to be operated by the movement of said structure in a reverse direction, and electrically operated means adapted when energized to render 40
- said structure operative with respect to operating the signaling apparatus. 45
8. In a train control system, a movable structure adapted to be raised and lowered, signal operating apparatus disposed in operating relation with the movable structure, means connected with said movable structure for operating said signal operating apparatus, when said structure is lowered, said means being normally inoperative with respect to operating the signal operating apparatus, electrically operated means adapted when energized to render the first named means operative with respect to operating said signal operating apparatus, means for electrically connecting said operated means with said structure, and means to move said structure and supply the same with an electric current. 50
9. In a train control system, a track, a vehicle to travel thereon, a structure mounted upon the vehicle and adapted to be raised and lowered, a ramp disposed in operative relation to the track and adapted to raise and lower said structure and supply current to the same, apparatuses for stopping the vehicle adapted to be operated by the upward movement of the structure, apparatus for actuating a signal adapted to be operated by the downward movement of said structure, electrically operated means for rendering said structure operative and inoperative with respect to operating said apparatuses, and means for connecting the electrically operated means with said structure whereby current may pass from the latter to the former. 55
10. In a train controlled system, a mechanically operated structure, a ramp to engage the mechanically operated structure, train stopping and signaling apparatus connected in circuit with the mechanically operated structure, a circuit connected with the ramp, and electrically operated means to control the operation of the mechanically operated structure with respect to operating the train stopping and signaling apparatus. 60
11. In apparatus of the character described, a mechanically operated structure, train stopping means, an element forming connecting means between the mechanically operated structure and the train stopping means and normally locking these parts together, and means including an electrical device to move the element for unlocking the mechanically operated structure and the train stopping means. 65
12. In apparatus of the character described, a movable structure, a ramp disposed in the path of travel thereof, train stopping apparatus to be operated by the movable structure, connecting means between the movable structure and the train stopping apparatus and normally serving to lock these parts together, an electrically operated means con- 70

- nected with the connecting means for operating the same to unlock the movable-structure and train stopping apparatus.
13. In apparatus of the character described, 5 a movable structure, a ramp disposed in the path of travel thereof, train stopping apparatus to be operated by the movable structure, connecting means between the movable structure and train stopping apparatus and 10 serving to lock these parts together at certain times, electrically operated means for operating the connecting means, and means electrically connecting the electrically operated means with the movable structure.
14. In an apparatus of the character described, 15 a movable structure, a ramp disposed in the path of travel thereof to move the same, train stopping means, and connecting means between the movable structure and train stopping means and adapted to 20 normally lock the movable structure with the train stopping means, electrically operated means, and connecting means between the electrically operated means and the first 25 mentioned connecting means whereby said first named connecting means will unlock the train stopping means and the movable structure, when the electrically operated means is energized.
15. In apparatus of the character described, 30 train stopping means, a signal device, a common mechanically operated structure to actuate at different times the train stopping means and signaling device, connecting means between the common mechanically 35 operated structure and train stopping means and signal device and serving to lock these parts together at certain times, and electrically operated means for effecting a relative 40 movement between the connecting means and the common mechanically operated structure.
16. In apparatus of the character described, 45 a ramp, a structure to be reciprocated by engagement with the ramp, train stopping means, and electrically controlled means to positively lock the reciprocating structure and the train stopping means together.
17. In apparatus of the character described, 50 a ramp, a structure adapted to be reciprocated by engagement with the ramp, train stopping means normally in locked engagement with said movable structure, and electrically operated means adapted upon being energized to break the locked engagement of the movable structure with the train stopping means, whereby the former 55 may be moved independently of the latter.
18. In apparatus of the character described, 60 a ramp, a circuit connected therewith and adapted to receive current when the track is "clear", a shoe to be moved by engagement with the ramp, a movable element connected with the shoe, train stopping 65
- means, connecting means between the movable element and train stopping means and serving to normally lock the same together, and electrically operated means adapted to be energized upon the engagement of the 70 shoe with the ramp when the ramp is electrified to operate the said connecting means, for unlocking the movable element and the train stopping means.
19. In apparatus of the character de- 75 scribed, a ramp, a structure to be moved by engagement with the ramp, train stopping means normally connected with said movable structure for movement therewith, and electrically operated means adapted upon being 80 energized to disconnect said movable structure and train stopping means, whereby the former may move independently of the latter.
20. In apparatus of the character de- 85 scribed, a ramp, a movable structure to be moved by engagement therewith, train stopping means, a rock shaft adapted to operate said train stopping means, said rock shaft being normally connected with said 90 movable structure for movement therewith, and electrically controlled means adapted upon being energized to disconnect the movable structure from the rock-shaft, whereby the former may move independently of the 95 latter.
21. In apparatus of the character de- 100 scribed, pivoted elements normally locked together whereby the movement of one will effect the movement of the other, electrically controlled means to unlock the pivoted elements, train stopping means actuated by one pivoted element, and mechanically operated means to move the other pivoted element.
22. In apparatus of the character de- 105 scribed, a ramp adapted to receive electric current, a movable structure adapted to be moved by engagement with the ramp, train stopping means normally in locked engagement with said movable structure, electro- 110 magnetic means adapted upon being energized to break said locked engagement, and means whereby said electro-magnetic means receives its current on contact of the movable structure with the ramp when said ramp 115 is electrified.
23. In apparatus of the character de- 120 scribed, a normally electrified ramp inclined upwardly from opposite ends, a movable structure adapted to be moved upward on contact with said ends on approaching the same from either direction, train stopping apparatus normally connected to be operated by the upward movement of said structure, and electrically operated means deriving 125 current from the ramp for disconnecting said structure from said train stopping means.
24. In apparatus of the character de- 130 scribed, a ramp rail having its terminal por-

tions inclined upwardly toward the center, a vertically movable guide bar, a shoe carried at the lower end of said guide bar and adapted to move the bar upwardly on riding up either incline, train stopping apparatus normally operative connections between said train stopping apparatus and said bar, and electromagnetic means deriving current through said shoe from said

ramp for disconnecting said normally operative connection. 10

In testimony whereof, I affix my signature, in presence of two witnesses.

THEODORE H. SCHREIBER.
